DETACHABLE HEEL TREAD

William Joseph Herald, Strathmore, Victoria, and
Robert Murray, West Brunswick, Victoria, Australia

Application November 28, 1950, Serial No. 197,878
In Australia December 5, 1949

3 Claims. (Cl. 36—42)

1

This invention relates to improved means for detachably fixing replaceable wearing pieces or base layers of leather or other suitable material to the undersides of the heels of boots and shoes.

The underside of the heels are subject to much wear in use in comparison with soles, uppers and other parts of footwear, and require renewal or replacement at frequent intervals during the useful life of a pair of boots or shoes in order to retain the shape and appearance thereof.

In manufacture, the base or bottom pieces are usually firmly secured as by pins or nails, and the replacement of such pieces in general, require skilled attention and cannot be undertaken by the user.

It has been previously proposed to provide replaceable wearing bases or pieces for the heels of boots and shoes, but hitherto the devices for securing the former to the latter have been complex, and costly, and means have been required in the heel for the sole purpose of detaching the wearing piece when replacement became necessary.

Now the principal object of this invention is the provision of simple, inexpensive and efficient means whereby a replaceable piece or base, may be detachably fixed to a shoe or boot heel so as to remain firmly attached thereto, but may be readily replaced by a user, upon becoming unduly worn.

A further object of the invention is to provide a replaceable wearing piece having projecting elements fitting sockets in a shoe heel, outward displacement of the projecting elements from the sockets being opposed by frictional resistance to movement of the former in the latter and by creation of partial vacuum in the sockets by outward movement of the projecting elements in the sockets.

Another object of the invention is to provide a replaceable wearing piece having holes in the projecting elements in communication with the sockets and extending partly but not completely through the elements, said holes responsive to predetermined wear of the elements connecting the interior of the sockets with the atmosphere and preventing the formation of partial vacuum in the sockets by outward displacement of the elements in the sockets.

A better understanding of the invention will be had from the following description of the practical exemplary arrangement as applied to the heel of a boot or shoe and depicted in the accompanying drawings.

2

In these drawings:

Fig. 1 is an elevation, partly in section, of the rear portion of a shoe fitted with a replacement heel piece according to the present invention;

Fig. 2 is a plan view of the replacement piece and associated attachment members removed from the shoe heel, and viewed in the direction of the arrow in Fig. 1;

Fig. 3 is a sectional elevation of an attachment member;

Fig. 4 is an elevation of an attachment member in position in the replacement piece.

Referring now to the drawings in more detail, there is formed in the heel 5 as by drilling, several cylindrical recesses 6 which extend upwardly from the underside of the heel for a required distance. Preferably, three of such recesses 6 are provided, two of which are located in the vicinity of the front corners of the heel, while the third is positioned centrally and near the rear rounded portion of the heel.

The replacement piece 7 to be applied to the heel formed with the cylindrical recesses 6 has the same external shape and size as the heel and is formed with the same number of holes or apertures similarly arranged and spaced exactly to correspond with the position and spacing of the recesses.

Accordingly, upon the replacement piece being applied to and centered upon the heel, the apertures in the former will be positioned in exact axial alignment with the recesses in the latter.

Mounted in each aperture in the replacement piece is a peg or plug 8 which is formed to closely fit the corresponding cylindrical recess in the shoe heel.

The pegs are provided with axial holes or recesses 9 which extend from the entry ends 10 of the pegs for a required distance towards the heads of the pegs and with axial extensions or blind holes 11 of smaller diameter than the holes or recesses 9 which extend part way through the heads.

The heads 12 of the pegs or plugs are of tapered or conical truncated form, the larger ends of the tapered heads being of maximum diameter tapering to a minimum diameter somewhat less than the diameter of the body 15 of the pegs which is of cylindrical form.

At the smaller ends of the tapered heads, peripheral shoulders 13 are formed and the opposite or entry ends 10 of the pegs are somewhat tapered to permit of easy engagement with the

cylindrical recesses 6 and with the apertures in the replacement piece.

The pegs or plugs 8, so constructed, are driven into the apertures in the replacement piece, so that the larger ends 12 of the tapered heads are flush with the wearing face of the replacement piece.

Upon the pegs being thus inserted into the apertures, the cylindrical body portions 15 of the former project from the apertures for engagement with the cylindrical recesses 6 of the heel.

As may best be understood by references to Fig. 4, in order to firmly secure the pegs in the replacement piece, a hollow tool or punch is placed over the projecting body 15 of each peg and is thrust under high pressure upon the inner face 16 of the replacement piece to force the contiguous material of the latter firmly against the shoulder 13 at the smaller end of the tapered head, thereby securing the peg against displacement.

The replacement piece 1 is secured to the heel by forcing the projecting peg bodies 15 into the corresponding recesses 6, air within the recesses and the axial holes 9 and 11 of the pegs being partially expelled as the same are driven into the recesses.

Upon a replacement piece being unduly worn, the axial extensions or blind holes 11 are opened by wearing of the tapered heads 12 of the pegs or plugs, thereby connecting the cylindrical recesses 6, holes 9 and 11 with the atmosphere, and permitting the replacement piece 1 to be removed, unopposed by atmospheric pressure with facility and replaced by another having projecting pegs or plugs engageable with the recesses 6 in the shoe heel.

The replacement pieces for each size of shoe or boot heel are interchangeable and are easily detached and replaced by a wearer, and moreover, if the replacement pieces on a pair of shoes are more worn at some parts than others, for instance, at the edge 17, they may be readily changed from one heel to the other so as to considerably extend their period of utility.

Furthermore, the replacement pieces may be constructed in sections, so that parts thereof apt to become worn, such as the rear heel portions, may be discarded and replaced by others having attachment pegs or plugs as above described. Accordingly, the effective life of the replacement pieces may be further extended.

The pegs or plugs may be constructed of wood, plastics or other suitable materials as may be found desirable or necessary.

We claim:

1. A replacement piece for a shoe heel hav-

ing secured therein and extending from a side thereof, a plurality of projecting attachment members fitting complementary sockets in the shoe heel and opposing displacement from the sockets by frictional resistance and creation of partial vacuum therein by outward movement in the sockets, said attachment members having longitudinal holes extending partly therethrough open at the ends within the sockets, whereby upon predetermined wear of said members the sockets will be connected with the atmosphere to thereby prevent the creation of partial vacuum in and facilitate extraction of said attachment members from said sockets.

2. A replacement piece for a shoe heel having secured therein and extending from a side thereof, a plurality of spacedly related pegs fitting correspondingly spaced complementary sockets in the shoe heel and opposing displacement from the sockets by frictional resistance and creation of partial vacuum therein by outward movement in the sockets, said pegs having axial holes extending partly therethrough open at the ends within the sockets, whereby upon predetermined wear of said members the sockets will be connected with the atmosphere to thereby prevent the creation of partial vacuum in and facilitate extraction of said attachment members from said sockets.

3. A replacement piece for a shoe heel having secured therein and extending from a side thereof, a plurality of spacedly related cylindrical pegs fitting correspondingly spaced cylindrical sockets in the shoe heel and opposing displacement from the sockets by frictional resistance and creation of partial vacuum therein by outward movement in the sockets, shoulders on the pegs engaging the side of the replacement piece and truncated heads on the pegs extending from the shoulders through the replacement piece and securing the pegs therein, said pegs having axial holes open to the interiors of the sockets terminating within the truncated heads, whereby upon predetermined wear the cylindrical sockets will be connected with the atmosphere to thereby prevent the creation of partial vacuum in and facilitate extraction of the pegs from the sockets.

WILLIAM JOSEPH HERALD
ROBERT MURRAY.
